(57) **CLAIM**

The ornamental design for a display screen with graphical user interface, as shown and described.

DESCRIPTION

This application is related to U.S. Utility Patent Application Ser. No. 18/097,022, filed Jan. 13, 2023 and entitled “Order Assembly for Multiple Points of Sale,” which is hereby incorporated by reference herein for all purposes.

The sole FIGURE is an image of a display screen with graphical user interface showing the new design.

The evenly spaced broken lines illustrate portions of the graphical user interface and environment that form no part of the claimed design. The dash-dot lines illustrate the boundary of the display screen and form no part of the claimed design.
